DESIGN FOR A SUGAR BOWL

Charles L. Sebring, Sebring, Ohio, assignor to
The Sebring Pottery Company, Sebring, Ohio,
a corporation of Ohio

Application September 13, 1934, Serial No. 53,277

Term of patent 7 years

To all whom it may concern:

Be it known that I, CHARLES L. SEBRING, a citizen of the United States, residing at Sebring, in the county of Mahoning and State of Ohio, have invented a new, original, and ornamental Design for a Sugar Bowl, of which the following is a specification, reference being had to the accompanying drawing, forming part thereof.

Figure 1 is a plan view of a sugar bowl showing my new design;

Fig. 2 is an elevational view of the sugar bowl shown in Fig. 1; and

Fig. 3 is a fragmentary sectional view taken on the line 3—3, Fig. 1.

I claim:

The ornamental design for a sugar bowl, as shown.

CHARLES L. SEBRING.
